UNITED STATES PATENT OFFICE.

ARTHUR F. STANLEY, OF NEW YORK, N. Y.

ELECTRIC BELL.

SPECIFICATION forming part of Letters Patent No. 423,707, dated March 18, 1890.

Application filed January 20, 1890. Serial No. 337,457. (No model.)

To all whom it may concern:

Be it known that I, ARTHUR F. STANLEY, a citizen of the United States, residing at New York, in the county of New York and State 5 of New York, have invented certain new and useful Improvements in Electric Bells; and I do hereby declare the following to be a full, clear, and exact description of the invention, such as will enable others skilled in the art 10 to which it appertains to make and use the same.

This invention relates to certain improvements in the construction of electric bells, whether the same be of the type known as 15 "vibrating" or that known as "single stroke."

Ordinarily such devices are constructed with an electro-magnet in proximity to a gong or other sounding structure with an armature presented to the blows of the electro-magnet, 20 and to such armature has been attached a length of spring-wire having at its outer end a ball or hammer for the purpose of delivering the blow to the gong. The construction of the parts has been such that three pieces 25 have been necessary; first, the armature; second, a piece of spring-wire, and, third, a separate ball or hammer screwed or soldered to the wire.

The object of my invention is to avoid this 30 complexity in the construction; and to that end my invention consists in forming the armature, its extension, and the hammer all in a single piece, as hereinafter described.

In the accompanying drawings, which form 35 part of this specification, Figure 1 illustrates the ordinary mode of construction, showing a flat armature, a spring-wire extension, and the ball or hammer, all three pieces being separately formed and then joined together for 40 use. Fig. 2 shows the blank which I have adapted in carrying out my invention. Fig. 3 shows the same with the shank twisted and bent so as to place the various portions in operative relation. Fig. 4 is a front elevation 45 of an electric bell with my invention applied to it, the cover being broken away, and showing the relations.

In practicing my invention I first stamp or 50 punch out of a sheet of iron or steel of proper thickness a blank having the armature por-

tion *a*, the shank *b*, and the disk or hammer *c*. I also prefer to leave at the lower end of the armature the projections *d*, which are afterward reduced with a milling-tool to form the trunnions for the proper pivoting of the 55 armature. As such bells are most generally constructed with the electro-magnets in the same plane as the plane of the gong, and as the hammer should be arranged to deliver its blow on edge, I simply twist the shank *b*, as 60 shown, and then bend the shank in a suitable manner, so as to occupy the ordinary position with relation to the gong. Constructed in this manner the total weight of the movable member of the bell combination is not any 65 greater than heretofore. Its inertia is not increased, while at the same time a durable structure is obtained, as there is no possibility of the shank becoming loose in its socket, nor of the bell becoming detached from its 70 supporting wire or shank, since all these parts are made in one integral piece of metal. By forming the blank straight, as shown in the drawings, and afterward twisting and bending it to the required configuration, there is so 75 little waste in the stamping or punching that it need not be taken into account.

Having thus described the nature and objects of my invention, what I claim is as follows:

1. As an article of manufacture, the herein-described electro-magnetic hammer for electric bells, consisting of the armature *a*, the shank *b*, and the disk or hammer *c* in one flat integral piece of iron or steel, with the disk 85 or hammer turned at substantially a right angle to the plane of the armature.

2. As an article of manufacture, the herein-described electro-magnetic hammer for electric bells, consisting of the armature *a*, the 90 integral shank *b*, and the disk or hammer *c* in one flat integral piece of iron or steel, the shank *b* being twisted so as to place the disk *c* at right angles to the plane of the armature.

In testimony whereof I affix my signature in 95 presence of two witnesses.

ARTHUR F. STANLEY.
